Inventor*

UNITED STATES PATENT OFFICE.

SAMUEL M. CODE, OF CHICAGO, ILLINOIS.

MAGNETIC VENTILATOR SYSTEM.

Original application filed January 5, 1927, Serial No. 159,184, and in Canada June 21, 1927. Divided and this application filed January 12, 1928. Serial No. 246,352.

This invention relates to closing mechanism that is automatic in operation to control the ventilator openings, more particularly for water-tight bodies described in 5 my pending application, Serial No. 159,184 this application being a division of said application.

One object of the present invention is to provide a positive closing mechanism that 10 will close the ventilator when the body tilts a predetermined distance.

Other objects and advantages will appear from the following disclosure of an illustrated embodiment of the present invention. 15

In the drawings:

Figure 1 is a sectional view in elevation of the closing mechanism embodying features of the present invention.

20 Figure 2 is a view taken substantially along line 2—2 of Figure 1.

A water-tight body 60, with double wall and insulation in centre, preferably of cork, of any suitable configuration, is securely 25 mounted on the frame 10, it having a windshield 61 secured in the front end thereof.

An opening 64 is provided, in this instance, in the top of the body for ventilation purposes. A closure 65 is hingedly mounted as 30 at 66 to close the opening 64 whenever desirable such as when the vehicle passes from land to water, it being desirable to exclude all water from within the body. As shown, the closure 65, is automatically operable re-

35 sponsive to the tilting of the body occurring when the vehicle passes from land to water so that there will be no possible chance of the interior of the body becoming flooded. Means for automatically closing the closure 40 65, in the present embodiment consists of electrical magnetic means including an electro-magnet 67 having an iron core 68 in the

form of a rod connected to the ear 69 fixed to the closure 65. A circular metallic member 70 is suspended in any appropriate manner from the body 60, as by means of the rods 71, there being confined within the ring 70, a freely swingable metallic pendulum 72 adapted to contact with the ring 70 when the body 60 is tilted. An electrical connection is established between the ring 70 and one terminal of the electro-magnet by means of the wire 73, the other terminal of the electro-magnet connected to a current source by means of a wire 74 so that the pendulum 72 50 and the ring constitute the ends of an electrical circuit. With this arrangement, the pendulum contacts with the ring 70, thereby energizing the electro-magnet 67 55 which effects movement of the closure 65 60 to its closed position.

Obviously, any appropriate means may be provided to maintain the closure over the opening, it being desirable that a latch be provided which requires a manual release of 65 the closure.

I claim as my invention:

1. In a vehicle, a frame, a water-tight insulated body on said frame having an opening, a hinged closure for said opening, and 70 electromagnetic means responsive to the tilting of said body to close said opening.

2. In a vehicle, a frame, a water-tight insulated body on said frame having an opening, a hinged closure for said opening, and 75 electromagnetic means responsive to the tilting of said body to close said opening, said electromagnetic means including a pendulum and a member encircling said pendulum constituting the ends of an electrical circuit. 80

In testimony whereof I have hereunto subscribed my name.

SAMUEL M. CODE.
